FOLDABLE DISPLAY-BOX.

1,333,893.

Specification of Letters Patent. Patented Mar. 16, 1920.

Application filed October 4, 1919. Serial No. 328,379.

To all whom it may concern:

Be it known that we, CHARLES BASHWINER, PHILIP BASHWINER, and ERNEST J. BRANDT, all citizens of the United States, residing, respectively, at Glenmorris, in the county of Queens and State of New York, at Jamaica, in the county of Queens and State of New York, and at New York, borough of Brooklyn, in the county of Kings and State of New York, have invented a certain new and useful Improvement in a Foldable Display-Box, of which the following is a full, clear, and exact specification.

This invention relates to a class of containers which is cut from a single blank and then folded into the form of a box.

Our invention has for its object primarily to provide a box or container for holding articles, such as merchandise, in a manner whereby the box with its contents may be displayed on a counter, show case and elsewhere so that it will attract the attention of persons as well as permitting suitable advertising matter to be conspicuously shown, and which is of a form whereby the contents of the box will be free from the liability of damage by the collection of dust or exposure to air as well as serving to protect the contents from being surreptitiously taken.

Another object of the invention is to provide a box which is cut from a single blank in a fashion allowing of being readily folded together for providing its various parts without the necessity of gluing, and which permits of the advertising matter desired to be displayed on the exterior of the assembled box to be accomplished by printing or embossing or otherwise inscribing only one surface of the blank, thereby saving the large expense usually attendant upon the making of many types of boxes of this class.

A further object of the invention is to provide a foldable display box whereby its simplicity of construction permits of a great saving in the consumption of the material of which it is made, and which is adapted to be produced in various sizes.

With these and other objects in view, the invention will be hereinafter more particularly described with reference to the accompanying drawing forming a part of this specification in which similar characters of

reference indicate corresponding parts in all the views, and will then be pointed out in the claims at the end of the description.

In the drawings, Figure 1 is a plan of a blank cut and scored from which the box is folded.

Fig. 2 is a perspective view illustrating one step in the folding process of the blank into the box.

Fig. 3 is a perspective view showing another step in the folding process of the blank.

Fig. 4 is a perspective, partly broken away, showing still another step in the folding process of the blank.

Fig. 5 is a perspective showing the blank when completely folded into the box.

Fig. 6 is a perspective of the folded box when arranged in position for displaying its contents.

Fig. 7 is a reduced sectional view, partly in detail, taken on the line 7-7 of Fig. 6, and

Fig. 8 is an enlarged fragmentary sectional view taken on the line 8-8 of Fig. 7.

The box is made from a blank 10, Fig. 1, which is cut or struck by the use of dies or otherwise from a single sheet of cardboard, paper or other foldable flexible material and then scored to provide a bottom member A, side wall members B, C, end wall members D and E, a lid member F, an adjustable sleeve member G, an easel member H and an upstanding display member I. All of these parts are integral, as shown, and when folded together the completed box is substantially rectangular.

The blank 10 has a body part 11 which is approximately rectangular in general outline, and the bottom A of the box is provided by scoring, at 12 and 13, transversely in spaced parallel arrangement the body part 11 of the blank. The body part 11 in spaced relation to one of its ends is scored, as at 14, crosswise with respect to the scoring 12 and 13, and the portion of the body part between the scoring 14 and the adjacent end of the body part is slotted, at 15, on alignment with the scoring 12, while the same portion of the body part in spaced relation to the slit 15 is likewise slotted, at 16, on alignment with the scoring 13. In spaced parallel relation to the scoring 13 the body part 11 is scored, at 17,

transversely from end to end, and portion of the body part from the juncture of the scoring 17 with the scoring 14 is slitted, as at 18, toward the second side edge of the body part.

5 The portion of the body part 11 of the blank 10 between the scoring 12 and its contiguous side edge provides the side wall member B, while the portion of the body part between the scoring 13, 17, 14 provides 10 the side wall member C. Both of the side wall members are of corresponding sizes, and the ends of these side wall members opposite to the scoring 14 are cut away on similar inclines, as at 20 and 21, respectively. The portion of the body part 11 of the blank between the scoring 17 and the scoring 19 provides the lid F which is, approximately similar in shape and size to the bottom A, and the portion of the body 15 part of the blank between the scoring 19 and the adjacent side edge of the body part provides a flap J which is associated with the lid F. The ends of the flap J may be cut on inclines, as at 22 and 23. The portion of 20 the body part of the blank between the slits 15 and 16 provides the easel member H, and across the central part of the easel member are spaced parallel scorings 24 and 25 which are also in spaced parallel relation to the 25 scoring 14. Centrally of the bottom A in proximity to the scoring 14 are two spaced aligned clips or tabs 26 and 27 each of which is formed by cutting the bottom somewhat semi-circularly so that the tabs may be bent 30 downwardly from the underside of the bottom for being engaged by the easel member H, as will be hereinafter more fully explained. The portion of the body part 11 of the blank 10 between the scoring 14, slit 35 15 and the adjacent corner of the body part provides a section 28 of the end wall member E of the box, while the portion of the body part of the blank between the slit 16, scoring 17 and scoring 14 provides a section 40 29 of the end wall member E. These two sections of the end wall member are adapted to be interlocked when folding the box, and to accomplish this, the central part of the edge of the section 28 adjacent to the 45 slit 15 is notched, as at 30, to provide a finger, as 31, while an end part of the section 29 of the end wall member is slitted, as at 32, for receiving the finger 31 when the sections 28 and 29 are detachably interlocked to 50 form the end wall member E.

The part of the scoring 17 of the body part of the blank 10 which is centrally of the section 29 of the end wall member E is slitted, at 33, and the portion of the body 55 part 11 forming the upstanding display member I consists of a panel which extends from the scored edge of the section 29 of the end wall member E in a direction, as shown in Fig. 1, alongside the lid F. The panel or display, member I may be of any suit-

able type, though the form illustrated is of considerably greater length than the width of the lid member F with its flap J. This panel or display member is centrally scored crosswise, at 34, to provide two foldable sections 35 and 36 so that the latter section may be bent over and upon the other section. Protruding from the edge of the free end of the section 36 of the display member is a tab or finger, as 37, which is positioned as 60 well as being arranged to adapt it to be removably inserted in the slit 33.

The adjustable sleeve member G is formed by cutting the blank 10 to provide a strip 38 on the end of the body part 11 of the blank opposite to the easel member H and the display member I, and included in this strip is the end wall member D of the box. The strip is of a width corresponding to the widths of the side wall members B and C, 65 while being of a length so that when folded in the fashion of a band it will be adapted to be arranged in an encircling manner on the exterior of the body of the box when assembled as well as being slidably adjustable 70 upwardly and downwardly relative to the box body. The end wall member D is formed by scoring the strip 38 crosswise, at 39 and 40, on alignment with the scoring 12 and 13, and at the intersection of the scoring 39 with the scoring 12 the strip is slitted, at 41, while at the intersection of the scoring 40 with the scoring 13 the strip is slitted, at 42. The slits 41, 42 serve to allow the sleeve to be hingedly adjusted on the 75 body of the box, as will be subsequently explained. The end wall member D is similar in size to the size of the end wall member E, and the parts of the strip 38 exclusive of the end wall member D is divided into side wall 80 sections, as 43 and 44 and end wall sections, as 45 and 46, by transversely scoring spaced parts of the strip, as at 47 and 48. The side wall sections 43 and 44 of the sleeve are slightly longer than the lengths of the 85 side wall members B and C of the blank 10, while the end wall sections 45 and 46 of the sleeve are of corresponding lengths as well as each being slightly longer than the length of the end wall member E of the blank. 90 The central part of one edge of the section 45 of the strip 38 is notched, at 49, to provide a finger, as 50 at the free end part of this section, and the central part of the section 46 of the strip at the scoring 48 is 95 slitted, as at 51, for reception of the finger 50 to detachably lock the sections 45 and 46 when disposed in overlapping arrangement to form the end wall E of the adjustable sleeve G.

In practice the blank 10 is folded to provide the box by bending the strip 38 of the sleeve G on the scoring 39 and 40 so that the sections 43 and 44 will be disposed in spaced opposition angularly with respect to the 100

end wall member D. The end wall sections 45 and 46 are bent at the scoring 47 and 48 so as to overlap, and by removably inserting the finger 50 of the section 45 into the slit 51 of the section 46 these sections will be removably locked together to form one end wall of the sleeve, while the end wall member D provides the second end wall of the sleeve as well as providing an end wall of the body of the box as shown in Figs. 2, 3, 4, 5, 6, 7, 8. By bending the end wall member D at the scoring, as 52, the sleeve may be swung upwardly and downwardly. The body part 11 of the blank is then folded at the scoring 12 and 13 to stand upwardly to provide the side wall members B and C of the body proper of the box, and the easel member H is bent on the scoring 14 toward the underside of the bottom A of the body of the box, while the sections 28 and 29 are bent on the scoring 14 so that they are in overlapping arrangement crosswise of the box body. By removably inserting the finger 31 of the section 28 in the slit 32 of the section 29 the end wall member E will be assembled. The body part 11 of the blank may then be folded at the scoring 17 and 19 so that the lid member F and flap member J may be swung upon the open top of the assembled body of the box as well as allowing the flap member to be inserted into the body of the box to lie against the side wall member B. When the sections 28 and 29 of the end wall member E are locked together the panel or display member I is folded at the scoring 34 so that the section 36 laps upon the section 35, and the tab 37 of the section 36 is inserted in the slit 33 of the section 35. This display member will then be in upstanding position above the assembled body of the box, though when the box is packed for shipping the display member is disposed so that it will lie upon the lid member F. The assembled sleeve G is then swung in an encircling fashion upon the exterior of the side wall members B and C, and upon the exterior of the end wall member E, the slits 41 and 42 of the strip 38 of the sleeve member enabling the sleeve at the end wall member D to assume the action of a hinge and the inclined edges 20 and 21 of the side wall members B and C permitting of free hinged action of the sleeve when moved over the body of the box.

To position the box on an incline on a counter, show case or elsewhere for attracting the attention of persons the easel member H is bent upon its scoring 24 and 25, and on being disposed downwardly and inwardly toward the underside of the bottom of the box the free edge of the easel member at the scoring 25 is removably seated under one of the tabs 26 or 27 according to the angle of incline in which it is desired to position the box. By slidably adjusting the sleeve G downwardly with respect to the bottom of the box the easel member will be encompassed by the sleeve which in turn will be firmly held for effectually supporting the box. On one or both of the exposed faces of the display member I, lid member F side wall members B and C, of the body of the box as well as on the exposed faces of the side wall sections 43, 44 and end wall section D may be printed, or embossed or otherwise inscribed suitable advertising matter. Moreover, all the printing may be done on one face of the blank, since the folding of all parts of the blank to provide the assembled box is accomplished by bending the box in an opposite direction to the printed face of the blank. When goods are packed in the box its contents may be removed therefrom by lifting the lid member F so that the flap will be removed from the body of the box, the lid member serving when closed to prevent the contents of the box from being damaged by exposure to dust and the air.

In the foregoing description we have embodied the preferred form of our invention, but we do not wish to be understood as limiting ourselves thereto, as we are aware that modifications may be made therein without departing from the principle or sacrificing any of the advantages of the invention, therefore we reserve to ourselves the right to make such changes as fairly fall within the scope thereof.

Having thus described our invention, we claim as new and desire to secure by Letters Patent:

1. A foldable display box, comprising a body with side walls and end walls and having an open top, a lid member with a flap member hingedly movable on one of the side walls of the body for opening and closing its top, and a display member upstanding from one of the end walls of the body so as to be swung downwardly and upwardly upon and from the lid of the body, said body and the said members being integral as well as being cut and foldably scored from a single blank.
2. A foldable display box, comprising a body with side wall and end walls and having an open top, a lid member with a flap member, hingedly movable on one of the side walls of the body for opening and closing its top, and a display member composed of two interlocked lapping sections hingedly upstanding from one of the end walls of the body so as to be swung downwardly and upwardly upon and from the lid of the body, said body and the said members being integral as well as being cut and foldably scored from a single blank in a manner whereby advertising matter provided on one face of the blank may be arranged so as to appear on the exterior of the parts of the box.
3. A foldable display box, comprising a

- 4
- body with side walls and end walls and having an open top, a lid member with a flap member, hingedly movable on one of the side walls of the body for opening and closing its top, a display member upstanding from one of the end walls of the body so as to be swung downwardly and upwardly upon and from the lid of the body, and a sleeve member hingedly adjustable upwardly and downwardly relative to one end of the box for positioning the body on an incline, said body and the said members all being integral as well as being cut and foldably scored from a single blank.
- 15 4. A foldable display box, comprising a body with side walls and end walls and having an open top, a lid member with a flap member, hingedly movable on one of the side walls of the body for opening and closing its top, a display member composed of two interlocked lapping sections hingedly upstanding from one of the end walls of the body so as to be swung downwardly and upwardly upon and from the lid of the body, and a sleeve member hingedly adjustable upwardly and downwardly relative to one end of the box for positioning the body on an incline, said body and the said members being integral as well as being cut and foldably scored from a single blank in a manner whereby advertising matter provided on one face of the blank may be arranged so as to appear on the exterior of the parts of the box.
- 20 5. A foldable display box, comprising a body with side walls and end walls and having an open top, a lid member with a flap member, hingedly movable on one of the side walls of the body for opening and closing its top, a display member upstanding from one of the end walls of the body so as to be swung downwardly and upwardly upon and from the lid of the body, and an easel member foldably adjustable at one end of the body for positioning the body on an incline, said body and the said members being integral as well as being cut and foldably scored from a single blank.
- 25 6. A foldable display box, comprising a body with side walls and end walls and having an open top, a lid member with a flap member, hingedly movable on one of the side walls of the body for opening and closing its top, a display member composed of two interlocked lapping sections hingedly upstanding from one of the end walls of the body so as to be swung downwardly and upwardly upon and from the lid of the body, and an easel member foldably adjustable at one end of the body for positioning the body on an incline, said body and the said members being integral as well as being cut and foldably scored from a single blank.
- 30 7. A foldable display box, comprising a body with side walls and end walls and having an open top, a lid member with a flap member, hingedly movable on one of the side walls of the body for opening and closing its top, a display member composed of two interlocked lapping sections hingedly upstanding from one of the end walls of the body so as to be swung downwardly and upwardly upon and from the lid of the body, and an easel member foldably adjustable at one end of the body for positioning the body on an incline, and a sleeve member hingedly adjustable upwardly and downwardly for engaging the easel member when supporting the body of the box, said body and the said members being integral as well as being cut and foldably scored from a single blank.
- 35 8. A foldable display box, comprising a body with side walls and end walls and having an open top, a lid member with a flap member, hingedly movable on one of the side walls of the body for opening and closing its top, a display member composed of two interlocking lapping sections hingedly upstanding from one of the end walls of the body so as to be swung downwardly and upwardly upon and from the lid of the body, an easel member foldably adjustable at one end of the body for positioning the body on an incline, and a sleeve member hingedly adjustable upwardly and downwardly for engaging the easel member when supporting the body of the box, said body and the said members being integral as well as being cut and foldably scored from a single blank in a manner whereby advertising matter provided on one face of the blank may be arranged so as to appear on the exterior of the parts of the box.
- 40 9. The combination, in a foldable display box having a substantially rectangular body with an open top, of a lid member with a flap member, hingedly movable on one of the side walls of the body for opening and closing its top, and a display member upstanding from one of the end walls of the body so as to be swung downwardly and upwardly upon and from the lid of the body, said body and the said members being integral as well as being cut and foldably scored from a single blank.
- 45 10. The combination, in a foldable display box having a substantially rectangular body with an open top, of a lid member with a flap member, hingedly movable on one of the side walls of the body for opening and closing its top, a display member upstanding from one of the ends of the body so as to be swung downwardly and upwardly upon and from the lid of the body, and a sleeve member hinged at one end of the body so that its second end may be adjustable upwardly and downwardly.

relative to the other end of the body, said body and the said members all being integral as well as being cut and foldably scored from a single blank.

5 11. The combination, in a foldable display box having a substantially rectangular body with an open top, of a display member composed of two interlocked lapping sections hingedly upstanding from one of the 10 ends of the body so as to be swung downwardly and upwardly upon and from the lid of the body, and a sleeve member hinged at one end of the body so that its second end may be adjustable upwardly and downwardly relative to the other end of the body, said body and the said members all being integral as well as being cut and foldably scored from a single blank.

12. The combination, in a foldable display 20 box having a substantially rectangular body with an open top, of a lid member with a flap member, hingedly movable on one of the side walls of the body for opening and closing its top, a display member upstanding from one of the end walls of the body so as to be swung downwardly and upwardly upon and from the lid of the body, an easel member foldably adjustable at one end of the body for positioning the body on 25 an incline, and a sleeve member having one end hinged at the end of the body opposite to the easel for being adjustable on the ex-

terior of the body upwardly and downwardly into and out of engagement with the easel when supporting the body, said 35 body and the said members all being integral as well as being cut and foldably scored from a single blank.

13. The combination, in a foldable display box having a substantially rectangular body 40 with an open top, of a display member composed of two interlocked lapping sections hingedly upstanding from one of the end walls of the body so as to be swung downwardly and upwardly upon and from the 45 lid of the body, an easel member foldably adjustable at one end of the body for positioning the body on an incline, and a sleeve member having one end hinged at the end of the body opposite to the easel for being 50 adjustable on the exterior of the body upwardly and downwardly into and out of engagement with the easel when supporting the body, said body and the said members all being integral as well as being cut 55 and foldably scored from a single blank.

This specification signed and witnessed this 3d day of October, A. D. 1919.
